PEDESTAL CHLORINATOR UNIT FOR SWIMMING POOLS OR THE LIKE

Wesley V. Bates and Bobby L. Bates, San Dimas, Calif., assignors to Jacketing Specialty, a corporation of California

Filed Aug. 1, 1968, Ser. No. 12,994

Term of patent 14 years

Int. Cl. D23—01
U.S. Cl. D23—3

FIG. 1 is a perspective view of a pedestal chlorinator unit for swimming pools or the like showing our new design;

FIG. 2 is a perspective view thereof with the pedestal fragmentarily shown for ease of illustration;

FIG. 3 is a side elevation view thereof; and

FIG. 4 is a fragmentary top plan view thereof.

We claim:

The ornamental design for a pedestal chlorinator unit for swimming pools or the like, substantially as shown and described.
